UNITED STATES PATENT OFFICE.

LOUIS HECTOR BACQUE, OF THREE RIVERS, CANADA.

GAS-BURNER.

No. 821,694.

Specification of Letters Patent.

Patented May 29, 1906.

Application filed May 27, 1905. Serial No. 262,601.

To all whom it may concern:

Be it known that I, LOUIS HECTOR BACQUE, of the city of Three Rivers, Province of Quebec, and Dominion of Canada, 5 have invented certain new and useful Improvements in Gas-Burners, of which the following is a full, clear, and exact description.

My invention relates to gas-burners; and the object is to provide a burner of greatly increased heat efficiency from burning a given quantity of gas. This object is attained by the accomplishment of three subsidiary objects, which are as follows: first, preventing the free access of cold air to the 15 flames of the burner; second, supplying the flame of the burner with a quantity of air that is susceptible of exact regulation and control and which is preheated by the waste heat of the burner itself; third, feeding to the 20 burner a mixture of gas and air that will also be controlled, preheated, and thoroughly mixed prior to combustion.

For better explaining the operation of my device I shall call "primary air" that which 25 is mixed with the gas in the mixing-chamber prior to combustion and "secondary air" that which is admitted to the flame of the burner after ignition to complete combustion.

In the drawings which illustrate my invention, Figure 1 is an elevation showing on the left the outer drum and on the right the inner preheating-drum. Fig. 2 is a vertical section through the center of the burner. Fig. 3 is a plan showing on the left the base- 35 plate and on the right the mixing-drum. Fig. 4 is a quarter plan view of the griddle. Fig. 5 is a section on the line X X of Fig. 1. Fig. 6 is a plan of the central heating-drum.

Referring to the parts, A designates a circular base-plate of any suitable material, preferably cast-iron, having at its circumference a raised annular ring A'. Surrounding a circular opening in the center of the plate is an annular collar A², while a plurality of 45 bosses A² are disposed between the collar and the ring A'. A shallow space A⁴ is left between the bosses A² for the passage of the gases.

A hollow stand or foot B is screwed to the 50 lower surface of the base-plate A and has a threaded portion B' adapted to be connected to a gas-pipe. Through the threaded portion is a channel B³, opening into an annular chamber B² for the admittance of the primary air and gases. A second opening B⁴ in

the bottom of the stand B is used to admit part of the secondary air.

A burner-plate E of any suitable material is placed upon the base-plate A in the manner shown in Fig. 2. This burner-plate has 60 a central tubular opening E², connected to the opening B⁴, and which forms the inner circumference of the annular chamber B², above referred to. The burner-plate E is so constructed that a plurality of mixing-chambers E³ and E⁴ are formed between the base-plate and the burner-plate. These chambers are connected by the shallow channels A⁴ and serve to change the velocity of the gases in passing through them and to thoroughly mix the gases with the primary air. In the upper surface of the burner-plate E, above the outer mixing-chamber E⁴, are a 65 number of apertures E', opening into the combustion-chamber, which apertures form 70 the points of ignition of the gas. A plurality of radial ribs E⁶ are carried upon the upper surface of the burner-plate E for the purpose of supporting artificial fuel, such as fire-clay or asbestos. 75

The burner-plate E carries near its outer circumference a raised annular ring E⁵, adapted to lie between and support in position an inner drum D and an outer drum C. The outer drum C is made of cast-iron or any 80 other suitable material and serves the purpose of preventing the cold air from entering the combustion-chamber. At the top of the drum C are a number of openings C', which admit secondary air into the annular chamber 85 C² between the drums C and D. A circular damper H, with holes corresponding to the openings C', serves to regulate and control the amount of air entering the chamber C². The inner drum D has a number of vertical 90 slits D' opening into the combustion-chamber and admitting secondary air thereto. 95

Over the central tubular opening E² in the burner-plate E is placed a cap F, as shown in Fig. 2. This cap is preferably formed with a conical lug F², depending into the opening E², and a number of legs F', which serve to support it upon the burner-plate E. The openings between the legs allow the passage of secondary air from the opening E² into the 100 combustion-chamber.

A damper J is placed over the opening B⁴ to regulate the supply of secondary air entering from this direction.

A griddle G with raised ribs G' is placed 110

over the combustion-chamber to support utensils thereon.

The operation of my device is as follows: Primary air and gas are admitted through the 5 pipe B³ into the annular chamber B² and thence into the first mixing-chamber E³. Here the velocity is impeded and the gases and air are mixed and heated by contact with the burner-plate E. The gases then 10 pass at a higher velocity through the shallow openings A⁴ into the second mixing-chamber E⁴ and from thence into the combustion-chamber through the apertures E'. During the passage from the first mixing-chamber 15 E³ the gases are in direct contact with the heating burner-plate E and are not only thoroughly mixed with the primary air, but enter the combustion-chamber at a high degree of temperature, which is the first step 20 toward increasing the efficiency of the burner. When secondary air is admitted into the openings C', it comes in contact with the pre-heating-drum D, and on entering the combustion-chamber through the apertures D' it has 25 reached a high degree of temperature. Moreover, the secondary air from this source strikes the combustion-chamber at ninety degrees or more to the angle of incidence of the primary gases, which secures the highest possible efficiency of combustion. Another supply 30 of secondary air is admitted through the opening B⁴ and is also preheated by contact with the burner-plate E and the cap F. The air from this source, which serves to complete 35 the perfect combustion of gas, also enters the combustion-chamber at an angle of ninety degrees or more to the angle of incidence of the primary gases. The purpose of the artificial fuel, which may be supported on 40 the ribs E⁶, is to prevent the escape of the gases until complete combustion has been ef-

fected and to arrest and store the heat which would otherwise escape at once. The objects attained, therefore, in my invention are the thorough mixing and preheating of the 45 primary air and gases and final complete combustion with preheated secondary air, as well as the exclusion of an excess of air from the flame.

While I have shown the preferred form of 50 burner as applied to the ordinary gas-stove, it will be readily understood that many variations in form may be made without departing from the spirit of my invention. I therefore reserve the right to all such modifications as fall within the scope of my invention.

Having thus described my invention, so that the same may be readily understood by those skilled in the art to which it appertains, what I claim, and desire to secure by Letters Patent, is—

In a gas-burner, the combination of a base-plate, a burner-plate mounted thereon, enlarged mixing-chambers connected by shallow channels between the base-plate and the burner-plate, a central air-passage through the base-plate, apertures opening therefrom at right angles to the combustion-chamber, a pair of outer cylindrical drums having an annular space between them, the inner of said drums having apertures opening into the combustion-chamber, and the outer drum having adjustable apertures for admitting air to the annular chamber.

In witness whereof I have hereunto set my hand in the presence of two witnesses.

LOUIS HECTOR BACQUE.
